UNITED STATES PATENT OFFICE.

ERNEST ALLEN, OF LOS ANGELES, CALIFORNIA.

REPEATING BURGLAR-ALARM.

971,813.

Specification of Letters Patent.

Patented Oct. 4, 1910.

Application filed October 5, 1908. Serial No. 456,350.

To all whom it may concern:

Be it known that I, ERNEST ALLEN, a subject of the King of England, who have declared my intention of becoming a citizen of the United States, residing at Los Angeles, in the county of Los Angeles and State of California, have invented a new and useful Repeating Burglar-Alarm, of which the following is a specification.

- 10 The main object of the present invention is to provide a burglar alarm which will give a succession of detonations on the opening of a closure, such as a door or window for an apartment or building.
- 15 Another object of the invention is to provide means for conveniently placing the device in and out of operative position.

The accompanying drawings illustrate my invention.

- 20 Figure 1 is a front elevation of a portion of the door showing the device applied thereto. Fig. 2 is an end elevation thereof, showing it in operative position. Fig. 3 is an end elevation of a portion of the door showing 25 the device applied thereto and in inoperative position. Fig. 4 is a vertical section of the device. Fig. 5 is an end view of adjoining parts of two window sashes showing burglar alarm device applied thereto.

- 30 Referring to Figs. 1 and 3 the device comprises a disk, wheel or rotatable member 1 mounted to rotate on a journal 2, extending from an arm 3, pivoted at 4 to a bracket 5, fastened by suitable means to a door or closure 6. Arm 3 extends obliquely outward and downward from its pivotal support 4 to allow the wheel 1 to rest on the floor 7 or other object in proximity to closure 6. A spring 8 connects said arm and the bracket 5 to draw the said arm toward the closure 6 and by reason of the obliquity of said arm to cause the same to bear against the floor 7. Wheel 1 is hollow and has inwardly projecting caps on the inner side of rim 10 and a 45 series of brackets, lugs or projections 11 which have angular extensions or cap holders 12 projecting therefrom in a circumferential direction relatively to the axis of the wheel; these projections being adapted to receive 50 fulminate caps or other detonating means 13, which fit on said projections so that they are frictionally held from such engagement.

- A spring hammer 15 is secured to the head or collar 9 on the fixed journal 2 of wheel 1 55 and carries at its end a head 16 adapted to impinge on the caps aforesaid. Head or

collar 16 may be integral with journal 2 and the latter may be riveted to arm 1, thus securing the wheel 1 in place while allowing rotation thereof. The said hammer may 60 consist of a piece of spring metal bent in bow-shape and enlarged at the end to form a head. The several parts of the apparatus including the disk, supporting arm and bracket may be cheaply formed of sheet 65 metal bent, brought to proper shape by bending or shaping, or they may be cast; in either case, the construction is inexpensive. Wheel or rotatable member 1 may have its rim provided with traction increasing means such 70 as felt or rubber 17, see Fig. 2, or with small projections as indicated at 17' in Fig. 4.

The operation of the device is as follows: When the door is closed and it is desired to set the device for giving notification of unwarranted opening of a door, the wheel 1 is turned down to position shown in Fig. 2 so as to rest on the floor, and caps 13 are placed on holders 12. If then the door is opened the wheel will run on the floor and the hammer 15 being stationary, the rolling motion of the wheel will cause the lugs 11 to pass the hammer. As each lug passes the hammer it first bends the hammer, the hammer and lug slipping on one another, until the 85 bending and slipping is such as to allow the hammer to slip over the lug, whereupon it springs forcibly to position to impinge against the next lug or against the cap placed thereon. As the result, the caps are detonated successively, giving a loud and repeated alarm and serving as an effectual warning that the door has been opened. In day time if it is not desired to use the device as an alarm, it is turned up in position 90 shown in Fig. 3. A spring 8 then serves to hold the device in this inoperative position. In using the device for a window alarm it may be applied to the top, say, of the lower sash, indicated at 18 in Fig. 5, the bracket 100 5 being fastened to the top stile of said sash and the wheel 1 being adapted to bear against the inside of one vertical stile 19 of the sash. In this case movement of either the upper or lower sash will cause rotation of the 105 wheel and detonation of the caps as aforesaid.

What I claim is:

1. In combination with a closure means and a floor, a rotatable member and a plurality of cap carrying means projecting therefrom, a pivotally supported arm carrying said

member, a spring hammer carried by said arm and lying in the path of rotation of said cap carrying means and operated thereby, and means for yieldingly holding said 5 rotatable member against said closure means or said floor.

2. In combination with a closure means, of a rotatable member, studs on said rotatable member, means on said studs for carrying caps, said means projecting forwardly from said studs, a pivotally supported arm carrying said member, and a spring hammer carried by said arm and extending in position to engage the cap carrying means 10 and adapted to be operated thereby.

3. In combination with a closure means,

of a rotatable member having a plurality of cap carrying means projecting forwardly in the path of rotation, a pivotally supported arm carrying said member, and a spring 20 hammer carried by said arm and extending into the path of rotation of said cap carrying means and adapted to be operated thereby.

In testimony whereof, I have hereunto set 25 my hand at Los Angeles California this 28th day of September 1908.

ERNEST ALLEN.
